UNITED STATES PATENT OFFICE.

WILLIAM B. MILLER, OF PITTSBURGH, PENNSYLVANIA, ASSIGNOR TO COPPER-DIE HORSESHOE COMPANY, OF PITTSBURGH, PENNSYLVANIA, A CORPORATION OF PENNSYLVANIA.

APPARATUS FOR ELECTRICALLY FORMING TOES AND HEELS ON HORSESHOES.

1,111,165.

Specification of Letters Patent.

Patented Sept. 22, 1914.

Application filed July 12, 1910. Serial No. 571,632.

To all whom it may concern:

Be it known that I, WILLIAM B. MILLER, a citizen of the United States, residing at Pittsburgh, in the county of Allegheny and State of Pennsylvania, have invented a new and useful Improvement in Apparatus for Electrically Forming Toes and Heels on Horseshoes, of which improvement the following is a specification.

10 The present invention relates to an improved device for electrically forming the heels and applying the calk members to the toes of horseshoes.

15 The object of my invention is to produce an apparatus by the use of which a complete shoe may be produced quickly.

20 To this purpose my invention consists in subjecting the blank shoe and toe to be secured thereon to an electric current, the greatest resistance thereto occurring at the 25 points of the shoe to be operated upon.

For a full understanding of the invention, reference is to be had to the following description and accompanying drawing, in 25 which—

Figure 1 is a side elevation of the apparatus, the outside plate or frame being removed; Fig. 2 is an elevation of the face of the operating table to which the shoe blank 30 is secured. Fig. 3 is a plan view partly in section; Fig. 4 is an elevation of the apparatus adjacent to the face of the operating table.

Referring to said drawings, 1 is a frame 35 in which a shaft 2 is suitably journaled; 3 is a cam rigidly mounted on said shaft and adapted to be actuated or thrown into various positions by the lever 4 rigidly secured on one end of said shaft. The inner 40 surface of said cam is provided with a number of grooves *a* which are adapted to engage with projections or serrations *b* upon the end of the die-bar 5 which is movably secured in bearings 6 secured to said frame.

45 The outer free end of said die-bar carries a die 7 which is adapted to engage with a toe 8 of the shoe 9, and the said toe is suitably heated as hereinafter specified, so that it may be thoroughly welded upon the shoe 50 by pressure exerted by said die through the medium of the bar and the cam heretofore described.

A support or operating table 10 is arranged opposite one end of the casing 1,

and the shoe blank 9 is clamped against the inner face of this support. For the purpose of holding the shoe blank in position a flap or clamping plate 11 is provided which is hinged to one side of the support 10 as indicated at 11^a, and has the swinging end thereof slotted at 11^b for engagement with a latch member 24. By means of this clamping plate the shoe blank is held securely in a vertical position against the support 10, the curved end of the shoe blank projecting downwardly and being arranged directly opposite the end of the die-bar 5. This die-bar 5 operates upon the toe of the shoe, while a cam 12 at the upper end of the support 10 is designed to operate upon the heel of the shoe. The said cam is mounted upon a rod or shaft 13, which is suitably insulated so that when the current is carried through the conductor 14, 15 and through the switch 16 and said shoe 9 to the ends of the blank, 75 the said ends become sufficiently heated as to enable the same to be turned at right angles to the blank by pressure exerted by said cam 12. It is understood that the current is not conveyed to the ends of the blank 80 as just described until after the toe or cork has been secured upon the shoe blank, as shown in Fig. 1, upon the completion of which operation the die-bar is withdrawn, thereby breaking the circuit which passes 85 from the conductor 14 to the conductor 17 through the die-bar to the toe of the shoe, thence back through the shoe to the plate 18 to the conductor 19, through the switch 20 back to the transformer (not shown), and 90 that the circuit just described, when broken by the withdrawal of the die-bar 5 as specified, passes through the shoe as heretofore specified.

23 is a clip former which is pivotally mounted upon the shaft 25 which is secured to the die bar 5 upon the lower side thereof. The said clip former normally swings downwardly from said shaft, as shown in Fig. 1, but is capable of being swung into a horizontal position beneath the die bar 5, as shown in Fig. 4, so that the forward curved end *j* thereof engages against the portion *k* of the shoe blank that projects beyond the toe, whereby when the said clip former 23 is moved forward by the die bar it presses the said portion *k* of the blank into the recess *m* of the operating table 10. The clip X is

formed upon the toe of the shoe by this operation. The said clip former 23 is held in a horizontal position by the supporting bars 21 and 22 which are pivotally mounted 5 upon the studs 26 and 27 and are adapted to be swung under the said clip former, as shown in Fig. 4, for the purpose as before stated of holding the clip former in operative position. It is to be understood that 10 after the completion of the operation of welding the toe calk upon the blank and before the heels are turned, as heretofore specified, the current is shut off and the clip former brought into operative position for 15 action upon the portion of the blank on which the clip is to be formed, this portion of the blank being still sufficiently heated to admit of the same being readily pressed into the form of the clip by the former.

20 Having described my invention, what I claim and desire to secure by Letters Patent is:

1. In a machine for forming the heels and toes upon horse shoes, the combination 25 of a frame, means to hold the blank shoe in operative position, means to convey an electric current to and localize the same at the heels and toes so as to produce a welding temperature at said points, and means to 30 press the heated shoe and calk sufficiently to weld the same, and means to turn the ends of the blank at right angles to form the heels.
2. In an apparatus for forming the heels 35 and toes upon horse shoes, the combination of a frame, a cam mounted in said frame, a die-bar actuated by said cam, a blank holder secured in said frame and adapted to hold the blank shoe in position during the opera- 40 tion, a cam adapted to press the ends of the blank horseshoe, at right angles to the length thereof, and means to convey a current and localize the same at the heels and toes of said blank shoe for the purpose of 45 making sufficient heat to produce a welding temperature therein as described.
3. In a machine for forming the toes upon

horseshoes, the combination of a frame, means for holding a blank shoe in operative position upon the frame, means for heating 50 a portion of the shoe blank to a welding temperature, a die bar mounted upon the frame for forcing a calk against the heated portion of the shoe blank to weld the calk in position thereon, and means upon the die 55 bar for acting upon the heated portion of the shoe blank to form a clip thereon.

4. In a machine for producing horseshoes, the combination of a frame, means for holding a blank shoe in operative position there- 60 on, means for heating a portion of the blank shoe to a welding temperature, a die bar mounted upon the frame, means coöperating with the die bar to force a calk member against the heated portion of the blank 65 shoe, a clip former movably mounted upon the die bar, and means for retaining the clip former in operative position, the clip former serving to act upon the heated portion of the blank shoe to form a clip 70 thereon.

5. In an apparatus for producing horse- 75 shoes, the combination of a frame, means for holding a blank shoe in operative position upon the frame, means for heating a portion of the blank shoe to a welding temperature, a die bar, means coöperating with the die bar to force a calk member against the heated portion of the blank shoe, a clip former pivotally mounted upon the die bar 80 and adapted to be swung into an inoperative position, and means for holding the clip former in an operative position, the said clip former being adapted to act upon the heated portion of the blank shoe to form 85 a clip thereon.

In testimony whereof, I have hereunto signed my name in the presence of two sub- 86 scribing witnesses.

WILLIAM B. MILLER.

In the presence of—

JOHN H. RONEY,

CLARENCE A. WILLIAMS.
